COMBINED BOILING, WASHING, CONDENSING, AND DRYING MACHINE

Filed April 5, 1924

2 Sheets-Sheet 2

INVENTOR:
John Wainwright Bowerbank
By Clatwin Company
Attns.

UNITED STATES PATENT OFFICE.

JOHN WAINWRIGHT BOWERBANK, OF KIDDERMINSTER, ENGLAND.

COMBINED BOILING, WASHING, CONDENSING, AND DRYING MACHINE.

Application filed April 5, 1924. Serial No. 704,540.

To all whom it may concern:

Be it known that I, JOHN WAINWRIGHT BOWERBANK, a citizen of the United States of America, residing at Kidderminster, in the county of Worcester, in the Kingdom of England, have invented new and useful Improvements in Combined Boiling, Washing, Condensing, and Drying Machines, of which the following is a specification.

This invention relates to a combined boiling, washing, condensing and drying machine, its object being to provide a quickly heated washer having powerful water and steam circulation, the steam and waste heat therefrom being utilized for heating a drying chamber, means being provided for returning all condensation water to the washer or boiler, means being provided for drawing air through the drying chamber, other means being provided for revolving a cage within the drying chamber when necessary and means being provided for heating the washer or boiler.

The various parts of the combined apparatus are particularly arranged for easy detachment and replacement as well as for quick fitting and adjustment in height or otherwise to suit particular conditions.

In order that the invention may be clearly understood and readily carried into effect, I will now describe the same fully herein-after with reference to the accompanying drawings, in which:—

Figure 1 is an elevation of the complete machine, parts being broken away; Fig. 2 is a plan of the dryer with top cover removed; Fig. 3 is a cross section of drying drum on line AB of Fig. 1; Fig. 4 is a cross section of drying drum on line CD of Fig. 1; Fig. 5 is a cross section of drying drum on line EF of Fig. 1; Fig. 6 shows a detail of an adjustable leg of the machine; Fig. 7 is an elevation of an alternative carrier for the clothes; Fig. 8 is a plan of said carrier; Fig. 9 is a detail.

The machine comprises a water boiler within a heat retaining shell 1, a burner beneath said boiler enclosed within a heat retaining ring 2, the boiler containing a water circulating device such as 36 as described in my co-pending application Serial No. 704,539, filed on the 5th April, 1924, to ensure a continuous and plentiful generation of steam to improve the boiling effect,

the whole of this apparatus preferably being of the kind described in my co-pending applications Serial Nos. 704,539, 704,537 and 704,538 respectively, filed conjointly with the present application on the 5th April, 1924. The lid 3 of the boiler is of truncated conical form as shown, and is provided with a steam outlet pipe 4 the upper extremity of which is formed with a water seal into which project or fit depending sides of an orifice 10, thus connecting said pipe with the interior of the double bottom 5 of the drying chamber. The double walls 6 of said chamber as described in the specification of my aforesaid application Serial No. 704,538 are provided with a door 7 sliding in guides 8 to give access to the interior, and the double bottom 5 is in communication with the interior of said walls 6 around the whole or part of its periphery. A number of perforations 9 are provided in the bottom 5 of the chamber by means of short tubes 9^a passing through each of the perforations 9, allowing the access of air to said chamber.

The top 11 of the chamber is slightly concave and is provided with a ring of perforations 12 and a gutter or trough 13 is secured beneath said perforations. A hollow shaft 14 passes vertically through the chamber and is journaled in the top and bottom thereof. At its lower end the shaft communicates with a flue 15 open to the interior of casing 1 at 15^a which conducts the waste heat of the burner up to aid in heating the drying chamber and as can be seen from co-pending application No. 704,539. A fan 16 integral with a pulley 17 is fitted upon the slotted upper end of the shaft 14, and belt 18 passing over pulley 17, guide pulleys 19 and handwheel or driving pulley 20 pivoted upon the frame 21 enables the fan and shaft to be rotated when desired. The fan comprises a number of vanes 22 secured upon triangular radial arms 22^a by adjusting screws 23, and rotates in close proximity above the top 11. A conical cover 24 surmounted by a vent pipe 25 encloses the fan, and is retained in position by clips 26 engaging the rim 27 thereof.

The operation of the machine is as follows:

The burner is adjusted so that the boiler is working at a convenient rate, and steam

passes through outlet pipe 4 into the chamber casing and quickly heats same. Articles to be dried are placed on carriers or in racks 28 of wire mesh upon a suitable frame 5 secured to the shaft 14, and rotated at intervals by means of the driving pulley 20. Air is thus drawn by the fan into the chamber through perforations 9 (the door 7 being closed), over the wet articles and through 10 perforations 12 into contact with the fan 16 and cover 24. The moisture taken up by the air from the articles during its passage through the drying chamber is condensed upon the fan and cover 24 and runs down 15 upon the top 11 to perforations 12 and thence into the gutter 13. A small conduit 29 removes the accumulated water from the gutter into the casing walls 5, where it ultimately finds its way back to the boiler. To prevent 20 the accumulation of condensation water on top of the pulley 17 a bore 30 is formed therein to drain the water on to the top plate 11, and a small conical cap 31 beneath the vent 25 assists in running off the water. 25 As a result practically no steam escapes into the atmosphere.

The steam entering the bottom of the casing is divided into two or more streams by 30 means of partitions, such as stout wires X filling the gap between the walls and passing up the sides, and in this manner the chamber is heated equally on all sides. The steam is condensed on the casing walls and runs continuously into the bottom and through 35 orifice 10 down pipe 4 and lid 3 back into the boiler. The water seals used at the junction of the lid and boiler and the pipe 4 and orifice 10 are kept continually full of water which overflows inwardly, as is shown in 40 my aforesaid co-pending application. This arrangement enables the lid 3 to be readily removed when desired and replaced correctly without difficulty. Any excess water may be removed by a tap in the bottom of the boiler. 45 The machine can be readily taken to pieces, and adjustment between the boiler and dryer is provided by adjusting nuts 32 and slots 33 in the legs 34 of the dryer attached to the boiler. The cross bars 35 of the dryer frame 50 may be used for airing the clothes.

An alternative method of supporting the clothes in the drying chamber is shown in Figs. 7 and 8. Radial vertical racks 36 are fitted around the shaft 14 and may be readily 55 detached or affixed as desired.

It is evident that by this machine the boiling of water and washing and drying of clothes or other articles may be effected by a single source of heat and without the escape of large volumes of steam, and considerable economy is thereby effected.

I claim:—

1. A boiling, washing, condensing and drying machine, comprising in combination, 65 a boiler, means for heating said boiler, water

circulating means within said boiler, a drying chamber, means for heating said chamber by the steam and waste heat from the boiler, means for returning condensation water to the boiler, and means for ventilating 70 said drying chamber and articles therein.

2. A boiling, washing, condensing and drying machine, comprising in combination, 75 a boiler, means for heating said boiler, water circulating means within said boiler, a drying chamber for the washed articles having a double walled casing, passages in said casing in communication with the steam outlet of the boiler, means for returning to the boiler steam condensed in said casing, a hollow shaft in said casing to take the waste heat from the boiler heating means, and means for ventilating said drying chamber 80 and articles therein.

3. A boiling, washing, condensing and drying machine comprising in combination, 85 a boiler, means for heating said boiler, water circulating means within said boiler, a drying chamber for the washed articles having a double walled casing, passages in said casing in communication with the steam outlet of the boiler, means for returning to the boiler steam condensed in said casing, a hollow shaft rotatably mounted in said casing, 90 means on said shaft for carrying the articles to be dried, a fan mounted on said shaft, means for rotating said shaft to ventilate said chamber and articles, and means for conducting waste heat from the boiler heating means to said hollow shaft.

4. A boiling, washing, condensing and drying machine, comprising in combination, 95 a boiler, means for heating said boiler, water circulating means within said boiler, a drying chamber having double side walls and bottom in communication with the steam outlet of the boiler, a perforated top to said chamber, a hollow rotatable shaft extending through said chamber, means on said shaft to carry articles to be dried, a fan on said shaft adjacent said perforated top, a conical detachable cover above said fan, a gutter disposed beneath the perforations in said top, means for conducting the condensation water from said gutter and casing to the boiler, and means for conducting waste heat from the boiler heating means to said hollow shaft.

5. A boiling, washing, condensing and drying machine, comprising in combination, 100 a boiler, means for heating said boiler, water circulating means within said boiler, a cylindrical drying chamber having a double 105 walled casing, communication between said casing and the steam outlet of the boiler, a sliding door to said casing, a perforated top to said chamber, a hollow rotatable shaft extending through said chamber, a plurality 110 of racks on said shaft to carry the articles 115

to be dried, a fan on said shaft extending above the perforated top, a pulley mounted on said shaft, a belt passing round said pulley and over guide pulleys on the exterior of the casing, a driving pulley for said belt pivoted upon the machine frame, a conical detachable cover above said fan, a gutter disposed beneath the perforations in said top, means for conducting the condensation water from said gutter and casing to the boiler, and means for conducting waste heat from the boiler heating means to said hollow shaft.

JOHN WAINWRIGHT BOWERBANK.
